UNITED STATES PATENT OFFICE.

HENRY C. THIEL, OF CHICAGO, ILLINOIS.

SIGNAL DEVICE.

1,252,059.

Specification of Letters Patent.

Patented Jan. 1, 1918.

Application filed March 6, 1917. Serial No. 152,704.

To all whom it may concern:

Be it known that I, HENRY C. THIEL, a citizen of the United States, residing at Chicago, in the county of Cook and State 5 of Illinois, have invented new and useful Improvements in Signal Devices, of which the following is a specification.

The signal device which is the subject matter of the present application for patent 10 is designed for use in connection with automobiles and other vehicles to indicate to the traffic to the rear of the vehicle the fact that the driver is about to make a turn or to bring the vehicle to a stop, and thus 15 eliminate or reduce to a minimum the liability of rear end collisions and other accidents.

It is the object of the present invention to provide a simple, reliable and easily 20 controlled visual signal device of the kind stated, and to this end it consists in a novel combination and arrangement of parts to be hereinafter described and claimed.

In order that the invention may be better 25 understood, reference is had to the accompanying drawing forming a part of this specification and in said drawing,

Figure 1 is a perspective view of the device with certain parts removed, and

Fig. 2 is a central vertical section thereof.

Referring specifically to the drawing, 5 denotes a lamp casing which is carried by a suitable bracket 6 mounted at any convenient place on the rear end of the vehicle 35 so as to face rearwardly. The lamp casing has a lens face, this lens not being shown in Fig. 1 in order that a better view of the interior of the lamp casing may be had. As shown in Fig. 2, the lens is divided into 40 upper and lower sections 7 and 8, respectively, the former being green and the latter red. These two differently colored lens sections are divided by a cement film 9 to prevent blending of the two differently colored light rays.

The casing 5 contains a standard incandescent electric lamp 10 obtaining current from any suitable source.

In line with the dividing line 9 between 50 the lens sections 7 and 8, the lamp casing 5 contains a horizontal partition 11 which divides the casing into upper and lower compartments. The lamp 10 is located in the lower compartment. The partition 11 is 55 hinged to the rear wall of the lamp casing, as shown at 12 so that it may be swung up-

ward as shown dotted in Fig. 2, in which position, the light rays from the lamp 10 pass into the upper compartment and the upper lens section 7 is illuminated. When 60 the partition is down, the upper compartment is shut off from the lamp 10, and the lens section 8 only being now illuminated. The lamp casing contains a ledge 13 on 65 which the partition rests when it is down.

The hinge 12 of the partition 11 is a rod journaled in the side walls of the lamp casing 5 and extending across the casing on the inside thereof near its rear wall. The 70 partition is suitably fastened at its rear edge to the rod, and by a coiled spring 14 it is held normally in lowered position seating on the ledge 13.

The hinge rod 12 projects at both ends 75 from the lamp casing 5, and one end has a crank bend 15, whereas its other end carries an indicator in the form of a flat plate 16 containing the inscription "Stop." This indicator is so positioned on the hinge rod 80 that it faces downward when the partition 11 is down, and when the partition is swung upward the indicator also swings into upright position to display the inscription, as shown dotted in Fig. 1.

A suitable actuating line 17 is connected 85 to the crank arm 15, the same leading to and being connected to the brake pedal of the car so that the signal is operated when the brake is applied. Of course, the signal may also 90 be operated manually.

The bottom of the lamp casing has a glazed sight opening 18 so that a license tag mounted beneath the lamp may be illuminated.

Normally, the partition 11 is down and the lamp 10 shines through the lower lens section 8 only. The indicator 16 is also down. When the driver wishes to make a turn or a stop, the application of the brake, 100 or a manual action of the connection 17 swings the partition upward, and also places the indicator upright in display position. The light rays now enter the upper half of the lamp casing and a green light is flashed 105 at the same time with the red light as a warning to the traffic behind the car. The indicator 16 will also be sufficiently illuminated from the lamp, but it is intended more particularly for signaling in the day time. 110 The lamp may have a lateral sight opening shown dotted at 19 in Fig. 1 to illuminate

the indicator 16. Upon releasing the connection 17 the spring 14 restores the parts to their normal position.

I claim:—

- 5 1. A signal device comprising a lamp casing having a lens face divided into two differently colored sections, a movable partition in the casing and dividing the same into separate compartments, one of the lens sections coinciding with one compartment, and the other lens section coinciding with the other compartment, a light source in one of the compartments, and means for moving the partition to place the compartments in communication.
- 10 2. A signal device comprising a lamp casing having a lens face divided into two differently colored sections, a movable partition in the casing and dividing the same into separate compartments, one of the lens sections coinciding with one compartment, and the other lens section coinciding with the other compartment, a light source in one of the compartments, and means for moving the partition to place the compartments in communication, said partition being normally in line with the dividing line between the lens sections.
- 15 3. A signal device comprising a lamp casing having a lens face divided into two dif-

ferently colored sections, a movable partition in the casing and dividing the same into separate compartments, one of the lens sections coinciding with one compartment and the other lens section coinciding with the other compartment, a light source in one of the compartments, means for moving the partition to place the compartments in communication, and an indicator on the outside of the lamp and connected to the partition to move therewith.

4. A signal device comprising a lamp casing having a lens face divided into two differently colored sections, a movable partition in the casing and dividing the same into separate compartments, one of the lens sections coinciding with one compartment, and the other lens section coinciding with the other compartment, a light source in one of the compartments, means for moving the partition to place the compartments in communication, a rod journaled in the wall of the lamp casing and carrying the partition, one end of the rod projecting from the lamp casing, an indicator carried by said projecting end of the rod, and actuating means for the rod.

In testimony whereof I affix my signature.

HENRY C. THIEL.
